PORTABLE RADIO CABINET

Melvin H. Boldt, Glenview, Ill., assignor to Zenith Radio
Corporation, a corporation of Delaware

Application June 1, 1959, Serial No. 56,153

Term of patent 14 years

(Cl. D56—4)

FIG. 1

FIG. 2

FIG. 3

Figure 1 is a front elevational view of my design for a portable radio cabinet as it appears with its handle in an upwardly extended carrying position;

Figure 2 is a perspective view of my design as it appears with its handle in a retracted position; and

Figure 3 is a fragmentary perspective view of a portion of the grille appearing on the front.

The side not shown is the same as the side shown, and the bottom and back are plain.

The dominant features of my design reside in those portions of the drawing shown by means of full lines.

I claim:

The ornamental design for a portable radio cabinet, substantially as shown and described.
